(57) **CLAIM**

The ornamental design for a light therapy panel, as shown and described.

DESCRIPTION

FIG. 1 illustrates a front perspective view of a light therapy panel;

FIG. 2 illustrates a front view of the light therapy panel thereof;

FIG. 3 illustrates a back view of the light therapy panel thereof;

FIG. 4 illustrates a left side view of the light therapy panel thereof;

FIG. 5 illustrates a right side view of the light therapy panel thereof;

FIG. 6 illustrates a top view of the light therapy panel thereof;

FIG. 7 illustrates a bottom view of the light therapy panel thereof;

FIG. 8 illustrates a back perspective unfolded view of the light therapy panel thereof; and,

FIG. 9 illustrates an enlarged view of the light therapy panel thereof.

The broken lines in the drawings illustrate portions of the light therapy panel that form no part of the claimed design. The broken line circle of FIGS. 1 and 9 defines the bounds of the enlargement and forms no part of the claimed design.

1 Claim, 9 Drawing Sheets
